[57] CLAIM

The ornamental design for a toilet seat lifter, as shown.

DESCRIPTION

FIG. 1 is a top view of the present invention with a toilet seat shown in phantom view;

FIG. 2 is an enlarged section view of the present invention taken along lines 2—2 of FIG. 1 with the toilet seat shown in phantom view;

FIG. 3 is a top view of the present invention;

FIG. 4 is a rear view of the present invention;

FIG. 5 is a side view of the present invention. The opposite side of the present invention is a mirror image of FIG. 5;

FIG. 6 is a front view of the present invention; and,

FIG. 7 is a bottom view of the present invention.

The broken line showing is for illustrative purposes only and forms no part of the claimed design.
